UNITED STATES PATENT OFFICE.

FREDERICK C. HERRICK, OF CLEVELAND, OHIO.

LATRINE FOR USE IN THE FIELD.

No. 873,749.

Specification of Letters Patent.

Patented Dec. 17, 1907.

Application filed October 1, 1906, Serial No. 336,815.

To all whom it may concern:

Be it known that I, FREDERICK C. HERRICK, a citizen of the United States, resident of Cleveland, county of Cuyahoga, and State 5 of Ohio, have invented a new and useful Improvement in Latrines for Use in the Field, of which the following is a specification, the principle of the invention being herein explained and the best mode in which I have 10 contemplated applying that principle so as to distinguish it from other inventions.

My invention relates to latrines and particularly to latrines for use in the field by troops in active service.

15 It is recognized that none of the methods of disposing of dejecta now in use by field troops is satisfactory. Latrines now in use are not efficient because they are either unsanitary or if sanitary the labor of construction and the difficulty of transportation of the requisites for their construction are such as to preclude their practical use as a part of a camp outfit for active field service.

The object of my invention is to provide a 25 latrine which is both sanitary and of a construction such as to necessitate in its erection a minimum amount of labor and also such as will permit it, and the tools for its construction, to be readily packed in a minimum 30 space and transported in a manner such as to render it practicable for use in active service in the field.

My invention consists of means hereafter 35 fully described and particularly pointed out in the claims.

The annexed drawings and the following description set forth in detail a device embodying my invention, the described means, however, constituting but one of various 40 forms in which the principle of the invention may be used.

In said annexed drawings:—Figure 1. represents a plan of the upper or portable part of my improved construction, a portion being 45 broken away to disclose the lower part thereof. Fig. 2. represents a front elevation of said upper portion, partly in vertical longitudinal section, showing also vertical sections of the earth in which cavities are 50 formed to constitute a part of the complete construction. Fig. 3. represents a vertical transverse section of said upper portion and the earth, taken on a plane passing through

the axis of one of the cavities. Fig. 4. represents a modified form of one of the ducts 55 forming a part of my invention and opened out flat for packing. Fig. 5. represents a vertical sectional view of a modified form of my invention and Fig. 6. represents a plan of the same with the cover partially broken 60 away.

A rectangular board A, Fig. 2, preferably of light wood of required strength, is formed with the desired number of apertures a , forming seats. This board is preferably reinforced by cleats a' secured to its lower surface, to prevent warping. Over each aperture a is a cover a^2 , Fig. 1, normally closed by springs a^3 suitably placed and secured to the board and covers respectively. Legs B B 70 are suitably fastened to the bottom of the board, preferably in the cleats, and are made to fit into holes bored therein so as to be readily removable. That portion of the board immediately adjacent to the apertures 75 I shall refer to hereafter as the "seat", and the remaining portion of the board and the legs constitute what I shall term the "seat-support".

In the bottom of the board and surrounding each aperture are formed grooves a^4 into which are snugly fitted the upper ends of ducts C, so as to be easily removable but at the same time insect-proof, that is capable of preventing absolutely the ingress or egress 80 of insects such as flies, mosquitoes, and so forth. These ducts may be made of galvanized iron or cheap stiff paper, card board, papier mâché, or veneer the latter materials being shellacked or otherwise treated to render them water proof. The ducts as illustrated are frusto-conical but may, if found preferable, be made cylindrical or of any other desired form. When made frusto-conical or pyramidal in shape they may be 85 nested for transportation. If desired they may be made to be opened out in sheets, as shown in Fig. 4, and provided with fasteners upon their edges, in the well-known manner of knock-down stove pipes. When made in 90 the last described form they may be packed and transported with great facility. Clips b are permanently secured to the outer surface of the ducts and near the upper edges thereof and are provided with holes through which 95 screws or nails may be driven to hold the 100

ducts securely in place in their grooves. It will thus be seen that flies and other insects are effectively excluded from the receptacle and its contents. To further insure a tight joint between the excavation and the duct, loose earth may be banked and packed around the exterior as shown in the right-hand portion of Fig. 2. As shown in Fig. 3, the ducts have a trend or inclination from the top portion rearwardly, whereby they are given a position in which the walls are as nearly as possible parallel with the path of the dejecta and the amount of the latter projected upon and adhering to such walls thereby reduced to a minimum.

In Fig. 5, I have illustrated a modified form of latrine in which but a single aperture is provided. The seat-support D consists of a ring d to the lower side of which are removably secured the legs d' . The duct d^2 is made with a flange d^3 which fits over the upper surface of the ring, and in a depression d^4 formed therein. The said flange forms the seat-proper. A suitable spring-actuated cover is provided to close the top of the duct, as shown.

In either of the above illustrated constructions it will be seen that the parts of the seat-supports are readily dismounted and packed so as to be easily portable. When the ducts are made of sheet metal they are washed and sterilized after use by burning out or by means of suitable chemical sterilizing agents. When made of combustible material they are preferably completely destroyed by burning or they may be crushed and buried in the excavations. The said excavations are formed by means of the ordinary clam-shell or auger post-hole diggers which are easily packed and transported in a small compass. When the latrine is to be abandoned the parts of the seat-supports are dismounted, cleansed and sterilized, the ducts removed, cleansed and sterilized or destroyed and the excavations filled up.

By means of my above described arrangement I obtain a latrine having all of the necessary requirements of sanitation, portability, cheapness, which requires in its construction a minimum of labor and such labor is performed with the aid of tools readily and easily packed.

Other modes of applying the principle of my invention may be employed instead of the one explained, and changes may be made in the construction herein described provided the means stated in the following claims or the equivalent of said stated means be employed.

I therefore particularly point out and distinctly claim as my invention:

1. In a latrine, the combination of a portable structure formed with a suitable seat-aperture, a duct suspended from said struc-

ture, and a receptacle formed by drilling an excavation in the soil, the lower end of said duct projecting into said receptacle, said duct presenting at all times an unobstructed passage from said aperture to said receptacle.

2. In a latrine, the combination of a portable structure formed with a suitable seat-aperture, a receptacle below said structure, and a duct detachably suspended from said structure, said duct presenting at all times an unobstructed passage from said aperture to said receptacle.

3. In a latrine, the combination of a structure provided with a suitable seat-aperture, a duct suspended and readily removable from said structure, and a receptacle, the lower end of said duct projecting into said receptacle.

4. In a latrine, the combination of a seat and seat-support forming a portable structure, a receptacle formed in the soil below said structure, and a duct detachably secured to the lower side of said structure and having its lower end projecting into said receptacle.

5. In a latrine, the combination of a seat and seat-support forming a portable structure, a receptacle formed in the soil below said structure, and a duct detachably suspended from the lower side of said support and having its lower end projecting into and readily removable from said receptacle, said duct presenting at all times an unobstructed passage from it to said receptacle.

6. A latrine comprising the combination of a portable structure including a seat and seat-support, a receptacle below said seat-support, a duct suspended from said support and projecting into said receptacle, said duct presenting at all times an unobstructed passage from the seat aperture to said receptacle, a cover for closing said aperture, and a spring suitably secured for keeping said cover normally in a closed position.

7. A latrine comprising the combination of a portable structure including a seat and seat-support, a receptacle below said seat-support, a duct detachably suspended from said support, having its lower end projecting into said receptacle and readily removable therefrom, said duct presenting at all times an unobstructed passage from the seat aperture to said receptacle, a cover for closing said aperture, and a spring suitably secured for keeping said cover normally in a closed position.

8. A latrine comprising the combination of a portable structure including a seat and seat-support, the latter including detachable legs, a receptacle formed by excavating the soil beneath the support, and a duct detachably suspended from said support and having its lower end projecting into said receptacle.

and readily removable therefrom, said duct presenting at all times an unobstructed passage from the seat aperture to said receptacle, a cover for closing said aperture, and a spring 5 suitably secured for keeping said cover normally in a closed position.

9. In a latrine, the combination of a receptacle, a seat-support formed with a seat aperture and a groove in its lower surface 10 surrounding said aperture, a receptacle

formed in the soil below said support, and a duct having its lower end projecting into said receptacle and its upper end fitting in said groove.

Signed by me, this 25th day of Sept., 1906. 15.

FREDERICK C. HERRICK.
